C. E. REED

UNDERREAMER

Filed Dec. 3, 1925

Clarence Edw Reed INVENTOR.

UNITED STATES PATENT OFFICE.

CLARENCE EDW. REED, OF WICHITA, KANSAS.

UNDERREAMER.

Application filed December 3, 1925. Serial No. 72,906.

My invention relates to underreamers for use in drilling wells for the purpose of enlarging a hole drilled below casing and has for its object to provide a construction of 5 underreamer which will be particularly adapted for use in wells of small diameter. Several forms of underreamers are known to the trade and in satisfactory use in wells of diameter from ten inches upwards and 10 some of them are used in wells of diameters as low as six inches but in the smaller diameters effective work done by the reamers is attended with extreme risk of the loss of the tools in the wells from breakage of the 15 reaming bits or cutters, which necessarily have to be of very small size.

In all types of underreamers with which I am familiar, it has been impossible to produce cutters of the small sizes required which 20 can be depended upon to have the strength necessary to stand up under the conditions to which they are subjected in the operation of underreaming. Very deep wells are of 25 recent development and have made necessary the use of casing of increased thickness to withstand the heavy pressure at greater depths. The practice of increasing the thickness of the casing and retaining the previous outside diameter has necessarily reduced the 30 interior diameter of the casing through which the drill must pass and increases the difference in diameter between the hole drilled below the casing and the diameter to which the hole must be enlarged by the underreamer to permit the casing to be lowered. The increased amount of work thus required 35 to be done by the underreamer is not particularly difficult in sizes above eight inches in diameter but in underreamers for wells of 40 smaller diameter increases difficulties which were already so great that they could not be met satisfactorily and the always present serious difficulty in the operation of any underreamer with which I am familiar has 45 been breakage and loss of cutters, necessitating fishing jobs which are expensive and have oftentimes resulted in the loss of the well.

The present invention is designed and provides an underreamer in which the cutters 50 are thickened in the section that usually breaks, and the cutters are formed to surround the lower end of the underreamer body, which provides a solid backing for the cutters when in operating position. This 55 construction gives a uniform distribution of the metal in the cutters and end of the un-

derreamer body, thereby developing the ultimate strength of the metal by eliminating weak points or sections, and the construction is such that the cutters can move only upward and downward. This design permits almost any desired distance of movement longitudinally of the reamer body in the movement of the cutters from collapsed to expanded position. 60

My invention provides a form of cutter which has large bearing surface to carry all loads and thrusts regardless of the direction from which the thrusts are imposed on the 65 body.

Another object of the invention is to provide reaming bits or cutters comprising a solid body only of novel form eliminating all wings, shanks or other extending portions of thin section upon which other types of 70 underreamer cutters must depend to hold the cutter against outward movement or movement in any direction, except downwardly. In this invention no operating thrusts at any time are taken by the means for drawing 75 the cutters against its bearing and abutment on the underreamer body.

With the objects above indicated, and other objects hereinafter explained, my invention consists in the construction and combination of elements hereinafter described and claimed: 80

Referring to the drawings:

Fig. 1 is a side view of the lower portion of an underreamer embodying my invention, 90 the underreamer cutters being in operating position and the cutter on the right side being shown in section.

Fig. 2 is a plan view looking upward at the bottom of the underreamer as shown in 95 Fig. 1.

Fig. 3 is a sectional view through Fig. 1 on the line A A.

Fig. 4 is a side view of an underreamer embodying my invention, the underreamer 100 being shown in position inserted in the well casing, the reaming bits or cutters being shown in collapsed position, and of slightly different form at their lower inner sides.

In the drawings, 1 indicates the underreamer body which is bored in its upper portion and screw threaded at the upper end. Within the bore of the body is mounted a coil spring 2 which surrounds a rod 3 which carries pin 5. The coil spring 2 bears at 110 its upper end against the flanged head 2^a of the rod 3 and bears at its lower end

against the shoulder 1^a of the body 1. The spring 2 tends to force the rod upward in the body. The pin 5 is mounted in the lower end of the rod 3 and pivotally supports the hangers 7.

In order to permit the cutters to pass through the well casing, the cutters are drawn downward to the collapsed position shown in Fig. 4, thus drawing the pin 5 and rod 3 down against the resistance of the spring 2.

Initial collapsing of the tool to the position shown in Fig. 4 may be done by manual operation in any suitable way. Usually a hook arrangement is placed over each cutter and as the tool hangs from the derrick or some other support, a block and tackle for instance may be used to collapse it.

20 The underreamer body 1 is centrally bored from its upper end to a point in line with the abutments 6. In line with the lower portion of the central bore 14 is formed a slot 15 extending laterally through the underreamer body and in which the pin 5 rides. In expanded position the pin 5 is at the upper end of the slot 15 and in collapsed (Fig. 4) position it is at the lower end.

30 To hold the cutters in collapsed position a pin 4 is passed through a hole 4^a in the rod 3 and by its engagement with the upper end of the slot 15 prevents the rod from being drawn up by the spring. When the cutters have been inserted within the casing the pin 4 is withdrawn and the underreamer may be lowered through the casing. For a detail disclosure of the expanded position and collapsed position see patent of Swan No. 1,507,444, Sept. 2, 1924, Figs. 5 and 3 respectively. The head of the rod 3 and the pin 4 limit and control the movement of the spring. The pin 5 is the means for attaching the hangers 7 to the rod 3, the hangers 45 being pivoted to the pin 5. The lower ends of the hangers 7 are threaded to receive a nut. There are two hangers 7 for each cutter. The lower end of the hanger 7 passes through a vertical hole 13 of which there are two in each cutter and screw threads 50 into a nut 8 which prevents the cutter slipping off the end of the hanger 7. The hole 13 in the cutter may be changed to a form other than round and an upset end could be used on the hanger 7 instead of a nut 8.

55 The underreamer body is formed with abutments 6. Two cutters are shown in the drawings, but three or more may be used in larger sizes. The lower portion of the underreamer body 1 is formed of an outline which, for want of a more accurate name, may be described, as seen in cross section, as two bulbs 11 whose stems connect to form a web 10. In Fig. 3 two cutters 9 are shown 60 surrounding the bulb portions 11 of the un-

derreamer body. The only way the cutters can be assembled on the underreamer body is by pushing them upwardly over the lower end of the bulb shaped ribs. The portion of the cutters designated by 12 surround the bulb portion of the underreamer body for half or more the length of the cutter and in large sizes the full length of the cutter as shown in Fig. 4. Adjacent to the abutments 6 the bulb and web shaped portion of the underreamer body is wider than at the end of the body, thereby forming a wedge which expands the cutters as they move upward longitudinally of the underreamer body to the operating position against the abutments 6. As clearly shown in the drawings, the shape of the cutters makes impossible any movement of the cutters except longitudinally of the body. Any desired length of longitudinal movement of the cutters may be readily obtained by changing the angle of the wedge. It will be noted that the cutters are thickest where the load falls. The cutters bear substantially their entire length around the bulb shaped portion of the underreamer body and particularly the upper half of the cutter, which is the section that usually breaks in other types of cutters.

It is of course well known that underreamers of this type are of the reciprocating cable tool system of drilling wells by percussion, the underreamer cutters striking a blow. The blow is concentrated on the extreme outer and lower edge of the cutter. These underreamers operate at the sides of a well enlarging a hole already drilled and in the nature of things it is impossible to expect or to obtain a uniform point of contact or direction of thrusts from the blow and the pounding under these conditions frequently breaks underreamer cutters, particularly the portion of the cutter used to fasten or hold it in the underreamer body.

65 My invention provides a form of underreamer cutter which does not operate in a slot or other recess within a body, necessitating thin portions of the cutters for retaining means and which at times and in fact often are subjected to violent thrusts from impact, but my invention provides a form of cutter which is new and combined with the shape of the underreamer body supporting it gives the maximum strength of the metal used and a thrust from any 120 direction is supported by the solid metal of the underreamer body.

70 As the method of inserting the underreamer in the casing by collapsing the cutters on the derrick floor and thus inserting them 125 within the casing and also the use of a spring to draw the cutters upward against the abutment, is well known in the art, no detail description has been thought necessary 130 in this specification.

Having thus described my invention, what I claim is:

1. In combination in an underreamer, a body having a downwardly tapered extension, said body extension comprising a web having ribs defining its tapering edges and presenting in cross section a pair of bulb-shaped enlargements connected by a relatively narrow web, a pair of oppositely disposed cutters having longitudinal undercut recesses adapted to receive said ribs and to be retained thereby upon said body, the mouths of said recesses being in width substantially no greater than the thickness of the web of the body, said body having an axial bore therein, a spring actuated axially movable rod in said bore, supporting hangers for said cutters, pivotally connected to said rod, each cutter being provided at its upper end with a pair of hanger receiving holes disposed on opposite sides of its rib receiving recess, said holes extending downwardly through said cutters and terminating in notches cut on the inner walls of said cutters, said hangers being adapted to be inserted in said holes and means engaging the ends of said hang-
- ers through said notches to secure the hangers to the cutters.
2. In combination in an underreamer, a body having a downwardly tapered extension, said body extension comprising a web having ribs defining its tapering edges and presenting in cross section a pair of bulb-shaped enlargements connected by a relatively narrow web, a pair of oppositely disposed cutters having longitudinal undercut recesses adapted to receive said ribs and to be retained thereby upon said body, the mouths of said recesses being in width substantially no greater than the thickness of the web of the body, said body having an axial bore therein, a spring actuated axially movable rod in said bore, supporting hangers for said cutters pivotally connected to said rod, each cutter being provided at its upper end with a pair of hanger receiving holes disposed on opposite sides of its rib receiving recess, said hangers being adapted to be inserted and secured in said holes to secure the hangers to the cutters. 50

In testimony whereof, I affix my signature.
CLARENCE EDW. REED.
